DESIGN FOR A FLOOR SURFACING MACHINE

Harold J. Pond, Minneapolis, Minn.

Application November 28, 1941, Serial No. 104,363

Term of patent 14 years

To all whom it may concern:

Be it known that I, Harold J. Pond, a citizen of the United States, residing at Minneapolis, in the county of Hennepin and State of Minnesota, have invented a new, original, and ornamental Design for a Floor Surfacing Machine, of which the following is a specification, reference being had to the accompanying drawing, forming part thereof.

The figure is a perspective view of the floor

surfacing machine, showing my design as it appears when viewed from one side thereof.

The appearance of the design is substantially the same when viewed from the other side thereof.

I claim:

The ornamental design for a floor surfacing machine, as shown and described.

HAROLD J. POND.
